UNITED STATES PATENT OFFICE

2,287,169

TILTING CLOSET ACTUATOR
MECHANISMEdward A. Fredrickson, Chicago, Ill., assignor to
Crane Co., Chicago, Ill., a corporation of Illinois

Application August 25, 1941, Serial No. 408,197

5 Claims. (Cl. 4—10)

This invention relates to a new and improved closet flush valve actuator mechanism and more particularly has for one of its principal objects the provision of a tripping mechanism for flush valves for use on folding or pivotable water closets in which it is desired to supply the closet bowl with a water seal or priming flush upon predetermined movement of the said bowl from an inoperative to an operative position. The mechanism set forth in the present application is an improvement over a similar mechanism set forth in United States Letters Patent No. 2,205,801 issued June 25, 1940. An example of the folding or pivotable type of closet bowl and dual type flush valve to which the mechanism is adaptable is illustrated and described in connection with United States Letters Patent No. 2,219,437, issued October 29, 1940, of which I am a co-inventor.

One of the more important objects of this invention lies in the provision of a flush valve tripping mechanism which operates the valve handle or actuator during the unfolding movement of the closet bowl and which, when the closet is in the unfolded or operative position, functions to effect a complete release of the valve handle from the tripped position.

A further important object of the invention is to provide a flush valve tripping device which is so constructed that it positively actuates the valve handle during the unfolding movement of the closet bowl, but does not actuate the valve handle during the folding movement of the closet bowl.

Another and still further important object of this invention is the provision of an easily adjustable and conveniently removable flush valve operating mechanism, and one which is readily adaptable to all sizes and types of bowls.

Other and further important objects of this invention will become apparent from the following specifications and accompanying drawings, in which

Fig. 1 is a side exterior view slightly in plan perspective of a folding closet bowl embodying my invention and in which figure the bowl is shown in the operative and unfolded position.

Fig. 2 is a partly sectional view of a dual type flush valve showing the relative positionings of the valve tripping mechanism with respect to the bowl when the valve and the closet bowl are in the operative position.

Fig. 3 is a fragmentary view of the flush valve and a novel tripping device showing progressively by the solid lines and the dotted lines the

manner in which the tripping mechanism permits the return of the closet bowl to the folded position without actuation of the flush valve.

Fig. 4 is a perspective view showing the valve handle in the tripped or operative position during the movement of the bowl and the valve from the folded to the unfolded position.

Fig. 5 is a vertical sectional view of the novel adjusting means incorporated in this device.

Fig. 6 is a detail of the adjustment arm of the device of this invention showing a front elevation thereof.

Fig. 7 is a top plan view of the device shown in Fig. 6.

Fig. 8 is a side elevation of the adjustment arm shown in Figs. 6 and 7.

Fig. 9 is a sectional view taken on the line 9—9 of Fig. 8.

Similar reference numerals refer to similar parts throughout the drawings.

The following brief description of a typical installation embodying a preferred construction of my invention is provided for illustrative purposes only and it is, of course, to be clearly understood that the invention may be applied to other devices in which a similar means of actuation is desirable.

As shown in Fig. 1, the folding closet bowl generally designated 1 is shown in the unfolded or operative position and is mounted upon a pivotable hollow trunnion 2, the said bowl and trunnion being interconnected by the water supply and discharge conduits 3 and 4, respectively. Flushing water is supplied to the fixture for the usual purpose through the inlet pipe 5 having connection with a suitable source of water supply (not shown) and with the direction of the water flow being taken as indicated by the arrow. Preferably, but not necessarily required, in connection with the control of such water supply, a stop valve 6 is provided so that in the event it is necessary to make adjustments upon the assembly, or to make repairs or inspections of the fixture, the stop valve may be used to shut off the water supply to the fixture. The latter valve is attached by means of a suitable pipe connection 7 to the lower portion of the hollow trunnion base or bearing 8.

The trunnion 2 comprises a hollow journaled tube which is preferably internally partitioned to cause one end to provide a suitable passageway for the inlet water supply between the bearing 8 and the conduit 3, and to cause the other end of the trunnion to provide a suitable passageway for the discharge water between the discharge

conduit 4 and the outlet 9. The trunnion 2, in addition to providing water passageways for the flushing operations of the bowl, also provides a journaled support for the bowl which permits the upward rotational movement of the bowl about the horizontal axis of the trunnion to the folded or inoperative position.

A dual type flush valve generally designated 11 is preferably, although not necessarily, attached to the side of the bowl 1 and interconnects the inlet conduit 3 with the usual internal flushing water passageways (not shown) of the bowl. A dual type flushing valve is provided in connection with the bowl for the manifold purposes of furnishing the bowl with an automatically supplied priming or sealing water flush upon movement of the bowl from the folded or inoperative position to the unfolded or operative position and, after the bowl has been used, to furnish a discharge flush upon manual tripping or operation of the flush valve in the preferred manner hereinafter described at greater length.

Attention is now directed to Fig. 2. The construction of the dual valve 11 comprises a casing which, as illustrated, is divided into two chambers 12 and 13, both of which are interconnected by means of the port 14. Each of the chambers 12 and 13 is provided with a valve closure member 15 which may be actuated by tilting the stem 16 thereof to one side. The manual means of operation provided to trip the valve comprises the foot pedal 17 which, when depressed, causes the lever 18 to move inwardly thus forcing the plunger 19 to move forward against the action of the spring 21 to tilt the stem 16. A tiltable handle 22 for independent actuation is preferably provided with a roller 23 near its outermost end and which functions in connection with the chamber 13 for forcing a plunger identical to 19 to move forward and to trip the similarly mounted valve contained in the chamber 13. The complete construction and manner of operation of the dual type flush valve, as has been stated, appears more fully in Patent No. 2,219,437 previously referred to.

More particularly, the present invention concerns an improved adjustable and removable mechanism for actuating the tiltable valve handle 22 and comprises essentially a vertically extending post 24 preferably threaded to the trunnion bearing 8, as shown more clearly in Fig. 5. The adjustable arm 26 mounted on the post 24 has pivotably mounted thereon the tripping pawl 27. As indicated, the threaded socket 28 into which the externally threaded end portion of the post 24 is engaged, is preferably integrally applied to the upper surface portion of the trunnion bearing 8. The upper end of the post 24 has an internally threaded bore 29 into which is threaded the bolt 31, the latter member being rotatably journaled in the top of the telescoping sleeve portion 32 of the adjusting arm 26. It is apparent that the construction provides that the arm 26 moves vertically, but non-rotatably upon rotation of the bolt 31. The arrangement of the integral supporting collar 33 within the sleeve 32 with the pin 34 above and outside the telescoping sleeve 32 results in the arm 26 and the bolt 31 being moved vertically together for desired adjustability. For convenience in obtaining rotation thereof, the head of the bolt 31 is provided with a screw-driver slot 36 thus enabling quick, easy adjustment of the height of the arm 26 and the associated tripping pawl 27 and avoiding the necessity of using wrenches

in relatively limited space. Thus the arm 26 together with the associated tripping pawl 27 moves vertically on the post 24. The pawl 27 has a weighted lower portion 37 which tends to normally maintain the pivotally mounted pawl in the desired vertical position as shown in Fig. 5. A rubber mounting 38 is preferably positioned circumferentially around the lower portion of the pawl 27 to act as a cushioning bumper when 10 the pawl subsequent to being actuated returns to its vertical position against the arm 26.

As best shown in Figs. 6 and 7, the telescoping sleeve portion 32 of the arm 26 is preferably split, being supplied with a longitudinal slot 39 at any convenient location around its periphery in order that the sleeve may be more securely attached to the post 24. Apertured ears or lugs 41 and 42 are provided on opposing edges of the slot 39 for the purpose of applying the bolts 43 to draw the edges of the sleeve slot together in a clamping action. Further vertical movement of the bolt 31 is prevented by use of the bolt 43 after the arm 26 and the associated pawl 27 have been properly set for the particular bowl selected for use. It is necessary to have compensating adjustments available in the tripping mechanism because the occurrence of slight discrepancies is common in the manufacturing of china bowls and similar vitreousware. The novel 30 advantages of this invention include vertical adjustment and setting means, as well as rotational adjustment of the telescoping sleeve 32 around the post 24.

The uppermost portion of the arm 26, as more 35 clearly shown in the sectional view of Fig. 5, extends within the recess 44 of the pawl 27; the latter member being rotatably mounted is attached to the arm 26 by means of the pin 46, and has its rotational movement limited in the 40 counter-clockwise direction by the rubber bumper 38 abutting the arm 26. The clockwise rotational movement of the pawl 27 is restrained to some extent by its weighted lower portion 37 and is further restricted by the end wall portion 15 of the recess 44. The loaded portion 37 of the pawl 27 is provided so as to effectively maintain the pawl in a substantially vertical position for reasons hereinafter explained at greater length.

As shown in Fig. 2, the bowl and flush valve 45 are in the unfolded or operative position. Assuming that it is desired to fold or to move the fixture is moved in a clockwise direction pivotally about the central axis of the trunnion 2 whereupon, as shown by the solid lines in Fig. 3, the roller 23 contacts the upper end surface portion of the pawl 27. Inasmuch as during the folding movement of the fixture it is not desirable to trip the handle 22 and to flush the bowl, the pawl 27 is made to rotate about the pin 46 and, as shown by the dotted lines in Fig. 3, the pawl assumes a tilted position thereby permitting the valve handle to proceed past the pawl without actuation of the handle 22. Upon further operation of the fixture towards the inoperative position the pawl is released from contact with the roller 23, whereupon the pawl 27 returns to its vertically extending position.

As shown in Fig. 4, the bowl and the flush valve are assumed to be in the process of being 70 moved from the inoperative to the operative position so far as flushing is concerned. At this stage of its operation, the roller 23, as shown, contacts with the upper surface portion of the 75 indexing pawl 27 and as the fixture 1 continues

to move pivotally downward in a counter-clockwise direction, the valve handle is tilted or canted upwardly as it strikes the upper corner of the pawl 27 to actuate the valve and to furnish the closet bowl with the water flush. Further movement of the bowl towards the lowered or operative position releases the tilted valve handle 22 and allows the latter to return to its normal untripped position, as shown more clearly in Fig. 1, thus completing its cycle of operation between the respective folded and unfolded positions of the closet bowl.

Having thus described my invention in a preferred embodiment thereof, it is to be expressly understood that various changes and modifications may be made without departing from the spirit and scope of the claims appended hereto.

I claim:

1. In combination, a foldable type closet bowl, a flush valve therefor, means for actuating the said flush valve upon unfolding movement of the said bowl, the said means comprising a tilttable valve actuator, tripping means for the said actuator, the said tripping means including a fixed, substantially vertical supporting means therefor, means on said supporting means for adjustably positioning the said tripping means, a pawl secured to the end of the said arm in the path of the said actuator, the said pawl providing index means, whereby upon folding movement of the said closet bowl the said pawl releases to permit untripped movement of the said valve actuator and upon unfolding movement of the said closet bowl the said pawl acts to trip the said valve actuator.

2. In combination, a foldable type water closet bowl having a dual type flush valve in cooperation therewith, said flush valve having respective manual and automatic means of actuation, the said automatic means comprising a tilttable valve actuator and a tripping means for the said actuator, the said tripping means including a post fixedly mounted relative to the said bowl, axially movable means for adjustably positioning the said tripping means relative to the said post, a pawl loosely secured to the end of the said post in the path of the said actuator, the said pawl having indexing means, whereby upon folding movement of the said closet bowl the said pawl is moved to permit untripped movement of the said valve actuator and upon unfolding movement of the said closet the said pawl is held relatively fixed to trip the said valve actuator.

3. In an arcuately movable water closet bowl having a flush valve in connection therewith, the said flush valve having automatic actuation, said automatic actuation comprising respective tilttable means and tripping means for the said tilttable means, the said tripping means including an

arm mounted upon a stationary base, the said arm including upper and lower portions adjustably movable relative to each other, a pawl in pivotal relation with the said upper portion of said arm and positioned in the path of the said tilttable means, the said pawl having a peripheral indexing means, whereby upon arcuate movement of said closet bowl in one direction the said pawl is pivotally moved permitting untilted movement of the said tilttable means and upon movement of the said closet bowl in an opposite direction the said pawl is moved to tilt the said tilttable means.

4. A foldable type water closet bowl comprising a dual type flush valve having respective manual and automatic means of operation, the said automatic means comprising a tilttable valve operator and a tripping means for the said operator, the said tripping means including substantially upright supporting means fixedly mounted relative to the said bowl and telescopically arranged means longitudinally movable relative to the said supporting means, threaded means for effecting longitudinal movement of said telescopically arranged means journaled in the upper portion of the said supporting means, a pawl loosely secured to the end of the said supporting means in the path of the said operator, the said pawl having indexing means whereby upon folding movement of the said closet bowl the said pawl is moved to permit untripped movement of the said valve operator and upon unfolding movement of the said closet the said pawl is held relatively fixed to trip the said valve operator.

5. A foldable type water closet bowl comprising a dual type flush valve having respective manual and automatic means of operation, the said automatic means comprising a tilttable valve operator and a tripping means for the said operator, the said tripping means including substantially upright supporting means fixedly mounted relative to the said bowl and telescopically arranged means longitudinally movable relative to the said supporting means, threaded means for effecting longitudinal movement of said telescopically arranged means journaled in the upper portion of the said supporting means, means for maintaining the said telescopically arranged means in predetermined relation with the said supporting means, a pawl loosely secured to the end of the said supporting means in the path of the said operator, the said pawl having indexing means whereby upon folding movement of the said closet bowl the said pawl is moved to permit untripped movement of the said valve operator and upon unfolding movement of the said closet the said pawl is held relatively fixed to trip the said valve operator.

EDWARD A. FREDRICKSON.
